CLAIM

The ornamental design for a mounting plate for a passive infrared motion detector with light fixture, as shown and described.

DESCRIPTION

FIG. 1 is a perspective view of a first embodiment of a mounting plate for a passive infrared motion detector with light fixture showing our new design, with the broken line showing of light fixtures being illustrative purposes only and forming no part of the claimed design;

FIG. 2 is an enlarged front elevational view thereof; the rear view is unornamented, contains no elements of the claimed design, and is not normally seen in ordinary use;

FIG. 3 is a right elevational view thereof; the left elevational view is a mirror image;

FIG. 4 is a bottom plan view thereof;

FIG. 5 is a top plan view thereof;

FIG. 6 is a perspective view of a second embodiment of a mounting plate for a passive infrared motion detector with light fixture showing our new design, with the broken line showing of light fixtures being for illustrative purposes only and forming no part of the claimed design;

FIG. 7 is an enlarged front elevational view of the embodiment of FIG. 6; the rear view is unornamented, contains no elements of the claimed design, and is not normally seen in ordinary use;

FIG. 8 is a right elevational view of the embodiment of FIG. 6; the left elevational view is a mirror image; and,

FIG. 9 is a bottom plan view of the embodiment of FIG. 6; the top plan view is identical to the top plan view of FIG. 5.
